FILLING STOP MOTION COMPELLER FOR LOOMS

Gustave A. Geeraert, Lawrence, Mass.

Application July 16, 1943, Serial No. 494,989

2 Claims. (Cl. 139—370)

This invention relates to a filling stop motion compeller for looms and has for an object to provide a circuit closer for the warp stop solenoid adapted to be struck by the dagger of the lay when the travel of the dagger is abnormally high, to stop the loom.

A further object is to provide a device of this character which is adaptable to looms using electric warp stop motion and is intended to utilize the warp stop motion knock-off when the filling stop motion fails.

Bending of fork wires caused by a shuttle leaving the shuttle box in a wobbly manner, or by a weaver throwing the shuttle through by hand, will prevent the dagger operating the filling stop motion shipper rod for stopping the loom. The same conditions occurs when the well in the lay, and other parts, become clogged with waste. Also loose securing screws of the fork wires extending out and striking back of the race plate, or striking the bottom of the reed, will render the filling stop motion inoperative, since because then the dagger will travel abnormally high and cannot operate the shipper rod.

With the above in mind a compeller is located in front of the center of the breast beam according to the present invention, and is wired to the warp stop motion solenoid, and is located at such a point on the filling stop motion stand carried by the breast beam as to be inevitably struck by the dagger traveling an abnormally high path, and close the solenoid circuit to operate the warp stop motion and compel the loom to stop when any of the above mentioned defects occur.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a portion of a loom, a compeller constructed in accordance with the invention being shown attached to the filling stop motion stand of the breast beam.

Figure 2 is a front elevation of the compeller.

Figure 3 is a vertical sectional view of the compeller taken on the line 3—3 of Figure 2.

Figure 4 is a bottom plan view of the compeller shown in Figure 2.

Referring now to the drawing in which like characters of reference designate similar parts in the various views, 6 designates the breast beam of a loom, and 1 the reciprocating lay which swings back and forth toward and away from the breast beam. Secured to the breast beam, midway of said beam is a filling stop motion stand 8 having an arm 9 adjustably fastened to the arm by a bolt 10, and having a cam 11. A tumbler 12 is pivotally mounted on a pivot stud 13 carried by the arm and is normally held by a spring, not shown, in the position shown in Figure 1, in which position a lug 14 on the tumbler abuts the upper face of the free end of a shipper rod 15 which shuts off the power when the tumber is engaged and actuated by the dagger in the event of failure or breaking of a thread.

The dagger 16 is secured to a dagger socket 17 which is pivoted on a bracket 18 carried by the lay 1. The dagger directed at the free end to project over the arm 9 and over the cam 11. A spring, not shown, acts to hold the dagger upon the cam and serves to cause the dagger to follow the curve of the arm as the lay oscillates, the normal travel of the dagger being such that a broken thread operation would cause the dagger to drop and strike the tumbler 12, following a line of travel indicated by the dot and dash lines and the legend "Normal" in Figure 1.

Fork wires 19 are secured to the lay 1 and project above a well 20 formed in the upper surface of the lay. The fork wires are connected to a shaft 21 which is connected by an arm 22 to the dagger socket 17. All the above are conventional loom parts.

Should the fork wires become bent, for reasons heretofore mentioned, such as waste accumulating in the well, or by the wires striking the reed 4, or by reason of loose attaching screws permitting the fork wires to strike the reed 4 or race plate 23 which causes the shuttle (not shown), the dagger 16 no longer can travel the path indicated by the normal dot and dash line marked with the legend "Normal" in case of a broken thread operation but instead will be deflected upwardly and held to travel a path materially above the normal path and indicated by the dot and dash line and the legend "Abnormal" in Figure 1. While traveling the abnormal path it is impossible for the dagger to strike the tumbler.

55

12 as it would during normal broken thread operation, to throw off the power.

Therefore I have interpolated in the abnormal path of travel of the dagger to stop the loom, a compeller designated in general by the numeral 24, disposed at the central front portion of the filling stop motion stand 8 on the breast beam 6, and adapted to form a circuit closer in the abnormal path of movement of the dagger for energizing the warp stop solenoid to shut off the power. The compeller comprises a base plate 25 of substantially rectangular contour formed of insulating material and provided with a longitudinal slot 26 and an opening 27 in one side communicating with the slot to permit the plate being attached to the filling stop motion stand by one of the securing bolts 28 which attach the stand to the breast beam 6. A brass spring 29 of inverted U form is secured to the plate 25 by bolts 30. A conductor 31 is secured to one of the bolts and is connected to the warp stop solenoid, not shown. When the dagger travels the abnormal path indicated in Figure 1 it contacts with the brass spring 29 and closes the warp stop solenoid circuit at this point to energize the solenoid and stop the loom.

From the above description it is thought that the construction and operation of the invention will be fully understood without further explanation.

What is claimed is:

1. A circuit closer for looms of the type having both a filling stop motion, and an electric warp stop motion, and wherein the filling stop motion is located in the path of travel of the dagger when a thread fails or is broken, a circuit closing device connected with the solenoid of the warp stop motion and fixed to the breast beam of the loom above the filling stop motion, and adapted to be engaged by the dagger when the dagger by reason of abnormal conditions fails to move in a path which would actuate the filling stop motion.
2. A circuit closer for looms of the type having both a filling stop motion and an electric warp stop motion, and wherein the filling stop motion is located in the path of travel of the dagger when a thread fails or is broken, a circuit closing device connected with the solenoid of the warp stop motion and fixed to the breast beam of the loom above the filling stop motion and having an insulating base plate with a longitudinal slot communicating with a side opening, and an inverted U-shaped contact spring on the plate adapted to be engaged by the dagger when the dagger by reason of abnormal conditions fails to move in a path which would actuate the filling stop motion.
